(57) **CLAIM**

The ornamental design for a pair of handles for a handbag, as shown and described.

DESCRIPTION

FIG. 1 is a front perspective view of a portion of the handbag shown in FIG. 1 and environmental matter;

FIG. 2 is a front view thereof;

FIG. 3 is a rear view thereof;

FIG. 4 is a side view thereof;

FIG. 5 is the other side view thereof;

FIG. 6 is a top view thereof;

FIG. 7 is a bottom view thereof;

FIG. 8 is a front perspective view of the portion of the handbag shown in FIG. 15, with handles shown in a raised position;

FIG. 9 is a front view thereof;

FIG. 10 is a rear view thereof;

FIG. 11 is a side view thereof;

FIG. 12 is the other side view thereof;

FIG. 13 is a top view thereof;

FIG. 14 is a bottom view thereof;

FIG. 15 is a front perspective view of the portion of the handbag shown in FIG. 15;

FIG. 16 is a front view thereof;

FIG. 17 is a rear view thereof;

FIG. 18 is a side view thereof;

FIG. 19 is the other side view thereof;

FIG. 20 is a top view thereof; and,

FIG. 21 is a bottom view thereof.

The broken lines depict portions of the handbag in which the design is embodied in environmental matter and is not considered part of the claimed design in those figures.
